Des. 133

John Burgess (a pupil of Gilbert Gérard) Troy, N.Y.
Letter Patent Design No. 133. dated 3d July 1847.

The schedule referred to in these Letters patent and making part of the same.

To all whom these presents shall come, Be it known that I, John Burgess of the City of Troy County of Rensselaer and State of New York have invented and produced a new design for Stoves, and that the following is a full and exact description reference being had to the accompanying drawings making a part of this specification.

The design is intended to be cut in bold relief and is composed of gothic doors & windows recessed, and inlaid the

around the inside with five carved mouldings, and filled in with fancy diamond ornaments as seen at (a a i b b in figs 1 & 2) in the drawings; on the tops of the arches of the gothic doors & windows and beneath the cornice is represented vines & scrolls as seen at C C C C figs 1 & 2, beneath the windows b to fig 2. in panels inlaid with twisted leaves as seen at d d. The corner & base are off figs 1 & 2 a finely carved with representations of different kinds of leaves; on the sides of each plate is a column with carved cornice and base as seen at 3333 figs 1 & 2.

I claim as my invention and desire to secure by letters patent the above design which is fully set forth in the drawing accompanying this description.
